UNITED STATES PATENT OFFICE

2,039,264

APPARATUS FOR BREAKING DOWN
MATERIAL

Ernst W. Seckendorff, White Plains, N. Y., assignor to The Jeffrey Manufacturing Company, a corporation of Ohio

Application August 15, 1933, Serial No. 685,233

3 Claims. (Cl. 83—11)

The improvements represented by this invention deal principally with an improved construction of rotary elements employed in connection with reducing or pulverizing apparatus, wherein material being finely reduced is subjected to the action of rapidly rotating reducing or pulverizing instrumentalities.

In machines of this general type the material to be reduced is fed into a casing in which there are mounted a pair of oppositely rotating overlapping pulverizing devices, each of these devices being provided with lugs operating in relatively close spaced relation with one another and with a grinding surface on the interior of the casing. Suction means are provided for creating air currents through the casing from the feed or charging side thereof to the discharge or outlet side, whereby the finely reduced or pulverized material is withdrawn from the pulverizing zone and delivered to the desired location. These air currents act upon the material to cause the same to pass first to the periphery of the pulverizing devices and then through the spaces between the lugs thereof and between the devices themselves, thence through the central portion of the reducing or pulverizing device on the discharge side of the pulverizing zone. The air currents act upon the material in a direction opposite to the direction of the centrifugal force exerted by the rotary pulverizing devices on the material, so that the air currents will act upon the pulverized or reduced material only when the particles thereof have become sufficiently fine so as not to be thrown outwardly from the pulverizing devices by the centrifugal force thereof. It has been the aim to maintain the distances between the oppositely rotating overlapping pulverizing devices and between the lugs thereof and the interior grinding surface of the casing as small as possible in order to assure the maximum reducing action being obtained.

One of the disadvantages of this type of apparatus as heretofore constructed, is the tendency of the material being reduced to pack between the various surfaces of the pulverizing zone. This packing materially reduces the output of the apparatus, increases the power consumption and lessens the degree of fineness of the particles of the resulting product, thereby substantially decreasing the efficiency of the machine.

This tendency of the material to pack may be overcome by the present improved construction, which enables the material to be maintained at all times in a substantially loose condition. The present invention is based upon the discovery that the desired looseness of the material may be obtained by proper proportioning of the number of pulverizing lugs on the pulverizing devices, and also by properly proportioning the number of such lugs relative to the number of pulverizing in-

strumentalities provided on the grinding surface of the casing, thereby enabling a reduction in the number of the lugs and in the number of such instrumentalities, with attendant increase in the interstitial spaces therebetween, while maintaining, or even increasing, the degree of fineness of the reduction heretofore obtainable in the previous designs of apparatus when these are operating at their maximum efficiency; and it has been found that the spaces between the respective pulverizing devices may be increased over those employed in the previous designs of apparatus, thus further maintaining the desirable degree of looseness in the material being reduced, without detriment to the reducing action thereon. A substantial economizing of the power consumption is also effected.

Another feature of improvement lies in the provision of the oppositely rotating overlapping pulverizing devices with pulverizing lugs of an oval or elliptical cross section, the major axis of the cross section in each instance being along the arc of a circle circumscribed by the center point thereof during rotation. This oval or elliptical cross section materially reduces the amount of wear on the lugs during service.

Other incidental improvements in the construction of the present apparatus have been made, which improvements will become apparent as the description proceeds, the novel features and combinations being more particularly pointed out in the appended claims.

The invention will be understood more readily by reference to the accompanying drawings, in which

Fig. 1 is a side elevation of a part of an installation embracing the present invention.

Fig. 2 is an end view of the apparatus of Fig. 1.

Fig. 3 is a view showing details of the construction of the pulverizer, the view showing, in section, the interior of the pulverizing housing and the mounting of the pulverizer, the drive motors and shafts of the rotors being shown in elevation for purposes of clarity.

Fig. 4 is a transverse section through the housing, taken on the line 4—4 of Fig. 3, looking in the direction of the arrows, the mounting of Fig. 3 being omitted, however, from Fig. 4.

Fig. 5 is a view similar to Fig. 4, but taken on line 5—5 of Fig. 3, looking in the direction of the arrows.

Fig. 6 is a plan view of the apparatus, showing the casing open for access to the interior thereof, the view illustrating the means whereby the casing may be opened, and the operation of the parts for opening the casing.

Fig. 7 is a perspective view of one side of the rotor employed on the feed or charging side of the casing.

Fig. 8 is a perspective view of the opposite side of the rotor of Fig. 7.

Fig. 9 is a perspective view of one side of the rotor employed on the discharge side of the casing the view illustrating the side of the rotor which overlaps the side of the rotor as illustrated in Fig. 7 when the apparatus is assembled.

Fig. 10 is a perspective view of the opposite side of the rotor of Fig. 9.

10 Fig. 11 is a perspective view of a grinding liner adapted to be positioned in the casing when the parts are assembled, the liner being adjacent to the impact lugs of the feed side rotor shown in Fig. 8 and also being adjacent to the pulverizing lugs of the rotor of Figs. 9 and 10.

Fig. 12 is a fragmentary sectional view showing the manner of securing the parts of the apparatus in interlocked relation.

Fig. 13 is a sectional view on the line 13—13 of Fig. 9.

Referring more particularly to the drawings, it will be seen that the invention embraces the unit A which is a pulverizing unit, which receives material to be pulverized, which material is delivered thereto from a storage hopper B and conveyor C, or any equivalent supply mechanism. As installed, the unit A is mounted on a base plate E and a foundation F, which may be of concrete or similar material. Drive instrumentalities, including a motor G which operates gears H, are employed for driving the endless feed conveyor C.

The conveyor C receives the material from the storage hopper B, and discharges the material into the feed hopper I of unit A. This feed hopper I has the throat 2 communicating with the interior of the unit A on the feed side thereof and is mounted on a flange 4 which is shown as being substantially flush with the top of casing 5, in which the pulverizer 6 and fan 7 are enclosed. The casing 5 is supported on the base plate or base E, which also supports the motor 8 for driving the fan shaft 9. The inner end of shaft 9 carries the fan side rotor element 10 of the pulverizer 6.

45 The endless conveyor belt 11 enters the hopper I and discharges the material into the feed side of unit A as previously stated. In the path of the discharging material is a permanent magnet 12 which is designed to remove tramp iron from the material. If desired, an electromagnet may be substituted for the permanent magnet 12 which is designed to remove tramp iron from the material. If desired, such electro-magnet substituted for the permanent magnet may be arranged so as to be energized whenever the feeding mechanism is operated.

A hollow circular closure 13 for the feed side of the casing 4 is provided with an integral platform 14 on which is mounted the motor 15. The shaft 16 of the latter extends inwardly and carries at its inner end the feed side rotor element 17. In the mechanism illustrated in the drawings, when the motor 15 is operated, the rotor 17 is rotated relatively to the casing 5 and the closure 13 in a direction opposite to the direction of rotation of the fan side rotor element 10, which is driven by the motor 8. The rotor 17 is keyed to the shaft 16 as indicated at 18.

70 The closure 13 is hinged relative to the housing 5, so that the closure 13, platform 14, motor 15, shaft 16 and rotor 17 may be moved axially of the shaft 16 away from the casing 5, and then swung laterally on vertical hinge instrumentalities so that both rotors will be freely accessible

for inspection, repair, or replacement, while being normally locked in position.

The casing 5 is provided with suitable sockets for the reception of pins 20 which are loosely fitted into the sockets and which are provided with a threaded, transversely extending base which receives the threaded lock bolts 21 which are held between the outstanding pairs of lugs 22 and lock thereagainst by the provision of the heads 23 on the bolts. A lateral extension 24 is slotted, as indicated at 25, to receive a pin 26 extending upwardly from the base plate E and welded, or otherwise permanently secured, to the base plate. When the lock bolts 21 are loosened, the closure 13 and associated parts 15 may be moved axially of the shaft 16 until at least the flange 13a of the closure 13 disengages from its engaging projection 5a of the housing 5, or, if necessary, the axial movement of the closure 13 may be sufficient to bring the pin 26 into engagement with the end of slot 25; in either event the movement being sufficient to enable the rotor 17 to clear the overlapping rotor 10, whereupon the closure 13 and its associated parts may swing arcuately upon pin 26 as a pivot 25 or hinge to take the open position, whereby the interior of the unit A becomes freely accessible. To facilitate this movement, the surface 27 of base plate E is machined perfectly smooth, and the platform 14 is provided with pockets 28, 30 adapted to receive oily waste for lubricating the surface 27 by drainage of oil through openings 29 in the bottom of the pockets, thereby enabling the platform 14 to slide more easily over the base plate and to prevent the smooth surface of the latter from rusting. Reverse movements enable closure 13 to be brought back into interfitting relation with the casing 5. For the purpose of properly guiding the return movement of closure 13, a guide bar 30 is suitably secured to the surface 27 of the plate, as by bolts or equivalent securing members 31, this bar being engaged by the platform 14 and guiding the platform in its movements relative to the plate. Shafts 9 and 16, are of course, in perfect alignment in order to provide correct clearance between the parts.

It will be seen that the closure 13, when in closed position, provides a feed chamber 33 for the material dropped from the endless conveyor belt 11.

A partition 34 removably mounted in casing 5, is provided with an opening 35 which registers with the opening 36 through the central portion of the fan side of rotor element 10. The partition 34 is formed with an annular flange 37 closely engaging a shoulder 38 of the casing 5. A removable cylindrical liner 39 abuts against the flange 37 of the partition 34, thereby holding the latter in place. The removable liner 39 is provided with comparatively wide circumferentially spaced webs 40, projecting into the interior of the liner, and which are arranged in substantially diametrical opposition. These webs 40 extend transversely parallel to the axis of the shafts 9 and 16. For saving material, the liner is recessed behind alternate ribs. At suitable diametrically opposed points, suitable openings are provided through the casing for the reception of set screws 41. The openings aforesaid are adapted to register with recesses 42 in the liner, these recesses being located behind opposite webs where the metal of the liner is thickened. The recesses 42 are tapered to receive the tapered ends 43 of the set screws 41. When as-

sembled, the recesses 42 are slightly offset relative to the set screws 41, the set screws thereby acting, when tightened, to aline the recesses 42 with the set screws 41 thereby forcing the liner 39 against the partition 34 in a wholly obvious manner, thereby clamping the partition tightly in position.

The spaced webs 40 are hardened as well as the inner surface or wall 44 of the liner, so as to provide an efficient breaking and abrading surface. Circular shoulders or supporting surfaces are provided on the annular flanges 47 and 48 for engagement by radial projecting ribs 40a of the liner 39 to center the liner or to hold the same concentric with the axis of the shafts 9 and 16. The ribs 40a, forming circumferentially distributed points of support, lessen the frictional contact to facilitate removal of the liner when desired, but nevertheless the frictional mounting of the liner, coupled with the clamping action of the set screws 41, is sufficient to hold the same in clamping position against the partition 34, and to maintain the opening 49 on its lowermost side in communication with the tramp pocket 50 in the base of casing 5. Further details of the liner structure will be set forth hereinafter.

It will be seen from Fig. 3, that the feed side rotor element 17 is provided with a plurality of radially extending blades 51, which project beyond the periphery of the rotor 17 and serve as beaters for the material to be pulverized as the material enters the casing 5 through intake opening 52, adjacent which opening the blades 51 are disposed. These blades are of substantial width and in addition to their serving as beaters on the material being pulverized, they act as blower or propeller blades, in conjunction with fan 7, to draw material through the intake 52 into the pulverizing zone 6 and to impart to the material a preliminary pulverization through the grinding action set up between the blades 51 and the grinding surface of the liner 39. This action will be referred to more fully hereinafter.

When the material to be pulverized falls to the bottom 53 of the chamber 33, it will tend to accumulate therein. If there is any tramp iron, the larger pieces will remain in the bottom 53 of the chamber 33, and may be removed when the closure 13 is opened. Smaller pieces of tramp material that may pass with the other material into engagement with the blades 51 will be ejected through opening 54 into pocket 55 in the bottom of closure 13. To facilitate this ejection, the edges of the bottom portion of this liner 39 are beveled, as shown at 56. Still other pieces of tramp material that may pass the crusher lugs will escape through the opening 49 into pocket 50 whence it may be withdrawn by removal of the door 57 of the pocket.

Inasmuch as the rotor disc 17 is closed, the material to be pulverized must find its way peripherally of the disc 17 between the grinding blades 51 into the pulverizing zone. This passage is facilitated by the coaction of fan 7 with blades 51. The fan 7, driven by motor 8, is adapted to produce a current of air from the feed side of the disc 17 into the hollow chamber of the feed side rotor 17 and the fan side rotor 58. Whatever material passes to the peripheral space surrounding the rotor 58 will be further crushed by impact of the particles of material against each other and by being thrown by the spaced rotor lugs against the liner 39.

While the air currents through the opening 36 tend to draw the crushed material through the

peripheral space between the lugs and the liner, and radially to the left of the rotor 58 as viewed in Fig. 3, this tendency is counteracted by radial fins 59, 59, which produce an effective seal to prevent the passage of coarse material between the back of the rotor 58 and the adjacent wall of the partition 34.

It will be noted that the feed side rotor 17 is provided with the radially extending ribs or vanes 51 which project beyond the periphery of the rotor 17 to adjacent the liner 39, forming the beater lugs 45. The vanes or ribs 51 are adjacent the feed opening 52 which is illustrated as being concentric with shaft 16 and of less diameter than the ribs or vanes 51. Because of this diameter, blades 51 exert a suction action on the incoming material and impel the material against the liner 39 for preliminary pulverization through impact against the liner, through action of the lugs 45 and the action of the particles on each other, this initial pulverization occurring in space 61.

Extending in the direction of the axis of rotation of the rotor 17 are a plurality of lugs 46, which are shaped as clearly indicated in the drawings, being preferably substantially elliptical in cross section, this shape being found to present a maximum surface to the material for pulverization thereof while being subjected to the minimum of wear. These lugs are spaced apart in such a manner that they will act as a screen to prevent passage therebetween, at operative speeds of the rotor, of any relatively coarse particles.

The fan side rotor 58 carries the pulverizing lugs 60 which overlap the lugs 46 of the feed side rotor. These lugs are of similar configuration to the lugs 46. It will be noted that the major axis of the lugs 46 and 60, in each instance, extends along the arc of a circle circumscribed by the center point thereof during rotation.

The material being pulverized passes peripherally of the feed side rotor 17 being subjected to the initial grinding action between the lugs 45 and the liner 39. Further pulverization occurs between the lugs and the liner 39, the material of course being substantially finer in this space than in the space 61 around the lugs 45. The centrifugal force exerted by the rotors rejects the coarser particles from between the space 62 between the rotors, only those particles in a sufficiently fine state of subdivision to be unaffected by the centrifugal force being drawn by the action of fan 7 through space 62 between the lugs 46 and 60.

Experience has shown that the number of lugs 60 on the fan side rotor should be such that not more than three lugs 46 on the feed side rotor should be in opposition with three lugs 60 on the fan side rotor at any given moment of time. If this ratio is increased, experience has shown that there is a tendency of the material being pulverized to pack around the rotors, and preferably the ratio should be less than one to three in order to assure a free flow of material continuously. This packing of the material is objectionable in that it increases power consumption, decreases the output of the apparatus, and reduces the fineness of the pulverization, as well as increases the wear on the respective parts. The keeping of the ratio within the indicated limit is an important factor in maintaining a free flow of the material through the apparatus, thus cutting power consumption very materially, increasing the output of the machine and fineness of subdivision of the particles of material delivered by the

apparatus, and reducing the amount of wear on the parts. As illustrated, rotors 17 and 58 rotate at high speeds in opposite directions.

In addition to the increased wearing qualities imparted to the rotor lugs by virtue of the curved surfaces thereof, the shape of the lugs increases the efficiency of the apparatus by virtue of opposing lugs exerting a Venturi action upon the material being pulverized, as the opposing lugs approach each other. This Venturi action is produced by the curving sides of the lugs acting as a funnel, and thus facilitates the drawing of the fine particles into the space 62.

Considering further the construction of the fan side rotor 58, it will be observed that the central portion of the rotor is extended into the limits of the opening 35 of the auxiliary partition 34, thus forming a rim around the opening 36 in the central portion of the fan side rotor. This rim 63 is beveled at such an angle that there will be no tendency of the material being pulverized to collect around the periphery of the opening. This angle in practice as found is substantially 45°, where coal is the material being pulverized. The beveled rim 63 also directs the material into the central portion of the fan 7.

The action of the fan 7 is increased by the shape and disposition of the webs 64, reinforcing the rim 63. These webs 64 may be substantially oval in cross section, being shaped as propeller blades and act in conjunction with the fan 7 to pull material from the pulverizing zone. This arrangement also results in a substantial saving of power.

The lugs 46 and 60 are so arranged that at a given instant there will be not more than a total of three lugs on the feed side rotor in direct opposition with three corresponding lugs on the fan side rotor, the point of opposition of the lugs on the two rotors occurring every 0.001 second. Where the outside diameter of the fan side rotor 58 is ten inches, for example, and the outside diameter of the feed side rotor 17 is seven and one-half inches, it has been found experimentally that maximum efficiency with respect to lowered power consumption and increased output and fineness of grinding, is obtained by providing six of the lugs 60 on the fan side rotor 58, nine of the lugs 46 on the feed side rotor 17 and three beater lugs 45. With such arrangement, see Fig. 4, it will be seen that just three of the lugs 46 are in opposition at any given instant with three corresponding lugs 60 on the fan side rotor 58. The intermediate lugs 46 pick up the material between the rotors and push it ahead until the point of opposition is reached, when the grinding action takes place; and as previously stated, the point of opposition of the lugs on the two rotors occurs every 0.001 second. The lugs 46 on the feed side rotor rotate with sufficient rapidity to act as a screen to prevent the coarse particles of material from passing through the spaces between the lugs.

Referring in more detail to the liner 39, it has already been said that the liner is provided with a plurality of grinding ribs 40, which project inwardly of the liner, and extend parallel to the rotor axes. Of these ribs, alternate ones only extend completely across the liner, as will be apparent from the drawings, the short ribs extending only across the zone of action of the fan side rotor. This means that an increasingly fine subdivision of the particles is carried out on the fan side rotor. However, not more than two of the lugs 60 which two lugs are diametrically opposed

are in opposition at any given instant with corresponding diametrically opposed liner ribs. It will also be seen that as the lugs 60 pass the ribs, the clearance between the lugs and liner is approximately double the clearance between the lugs and the ribs. This increased clearance between the ribs enables the material to be pulverized to be swept freely along by the action of the lugs and air currents, and prevents any tendency of the material to pack between the respective surfaces. Experience has shown, also, that a greater number than two coincidences will tend to obstruct the passage of air irrespective of the size of the rotor.

On the feed side rotor 17, only one of the lugs 45 is in opposition, at any given time instant, with a rib on the liner.

It will be noted from the drawings that the feed side rotor 17 is mounted on the shaft 16 through a hub 65 adjustably keyed to the shaft 20 through a set screw 66, and the fan side rotor 58 likewise is adjustably keyed to the shaft 9 by a set screw 67 and hub 68. Fan 7 is secured on the shaft 9 between the end of the rotor hub 68 and the motor 8.

The following data is given as illustrative of the dimensions and operative factors of a typical operative device constructed in accordance with this invention, it being understood that these are given merely by way of an illustrative example, and may be varied in any manner as may be necessary to fulfill the requirements of a particular installation, the data being based upon coal as the material being pulverized.

Diameter of fan side rotor	inches	10	35
Diameter of feed side rotor inclusive of beater lugs	inches	10	
Diameter of feed side rotor exclusive of beater lugs	inches	7½	40
Diameter of liner between ribs	do	11	
Diameter of liner intermediate adjacent ribs	inches	11¾	
Diameter of auxiliary partition on fan side of casing	inches	12½	45
Outside diameter of central rim on fan side rotor	inches	5½	
Inside diameter of central rim on fan side rotor	inches	6 1/8	
Diameter of rotor bushings	do	2	50
Diameter of rotor shafts	do	1	50
No. lugs on fan side rotor		6	
Length of lugs	inches	2 1/8	
Major diameter of lugs	do	1 1/8	
No. lugs on feed side rotor		9	55
Major diameter of lugs	inches	1 1/2	55
No. beater lugs on feed side rotor		3	
Length of beater lugs on feed side rotor	inches	1 1/4	
Width of beater lugs on feed side rotor	inches	1 1/2	60
No. pulverizing ribs on liner		8	
Distance between lugs on fan side rotor and lugs on feed side rotor	inch	½	
Distance between lugs on fan side rotor and ribs on liner	inch	½	65
Distance between beater lugs on feed side rotor and ribs on liner	inch	½	
Time interval for frequency of lugs on both rotors to be in opposing positions	second	0.001	70
Speed factors, based on 3 H. P. fan side motor full load speed of 3440 R. P. M. and 2 H. P. feed side motor full load speed of 3490 R. P. M.			

Peripheral speed fan rotor lugs, outside diameter	feet per minute	9,008
Peripheral speed fan rotor lugs, inside diameter	feet per minute	7,542
5 Peripheral speed feed rotor lugs, outside diameter	feet per minute	6,795
Angular velocity fan rotor:		
Lugs per second		344
Time interval of lugs	second	0.0029
10 Angular velocity feed rotor:		
Lugs per second		523.5
Time interval	second	0.0019

The "number of lugs per second" is obtained by multiplying the R. P. M. of the motor by the 15 number of lugs and dividing by sixty seconds.

The "time interval" is the fraction of a second 20 between lugs, or the time required for one lug to move the distance of its spacing. This value is obtained by dividing one second by the number of lugs per second.

From the above data, the details of construction of the rotors for any given installation may be determined. When pulverizing coal experience has shown that irrespective of the size of 25 the rotors, best results are obtained by maintaining substantially constant at 0.001 second the time interval for the frequency of the lugs on both rotors to be in opposing positions, and the 30 number of lugs on the rotors will be dependent upon the speed of rotation of the rotors. Taking the above angular velocities as the basis for determining the number of lugs on the feed and fan side rotors, the following formulae may be 35 used:

For the feed side rotor,

$$Z_1 = \frac{62,370}{N_1 + N_2}$$

40 For the fan side rotor,

$$Z_2 = \frac{41,580}{N_1 + N_2}$$

Where Z_1 =number of lugs on feed side rotor

45 Z_2 =number of lugs on fan side rotor

N_1 =number of revolutions of feed side rotor

50 N_2 =number of revolutions of fan side rotor

55 Experience has indicated that good results will be uniformly obtained by maintaining the clearance between the feed and fan side rotors and between rotors and liner ribs at approximately one-half inch, independent of the size of the rotor.

The numerical quantities in the above formula are obtained by adding together the R. P. M. of the two motors as given in the specific illustration and multiplying this total R. P. M. by the 60 number of lugs on rotors of the above illustration. The above specifically described construction may be taken as a standard or basis from which to work.

65 The construction as detailed above is designed, when grinding coal, to give a product substantially 80% of which will be not greater than 200 mesh. The fineness of pulverization may be adjusted, if desired, by varying the distance between the rotors by adjusting the set screws 66 and 67.

70 The base plate E is provided with a plurality of channel members, indicated at 69, which are

adapted to be embedded in a concrete, or equivalent, foundation when the apparatus is mounted for service. The top surface of the plate E is machined very smooth to facilitate the movement of closure 13, and in order to readily level 5 the unit when it is installed on its supporting foundation structure, grout holes 71 are provided in the plate E, through which holes any necessary concrete may be introduced for leveling the machine.

10 It will be further noted that the fan compartment is provided with ports 70 for introduction of supplemental air to the fan 7.

Obviously those skilled in the art may make 15 various changes in the details and arrangement of parts without departing from the spirit and scope of the invention as defined by the claims hereto appended and I wish therefore not to be restricted to the precise construction herein disclosed.

20 Having thus described and shown an embodiment of my invention, what I desire to secure by Letters Patent of the United States is:

1. Apparatus for breaking down materials 25 comprising the combination with a casing, of an auxiliary partition enclosed within the casing, the partition having an opening therethrough for passage of material being pulverized, a pulverizing rotor adjacent the partition on one side thereof comprising a disc having a central opening therethrough for passage of material and a rim around the opening extending into the partition opening, a suction fan on the opposite side of the partition and propeller blades mounted on the rotor across the opening therethrough to supplement the action of the fan to feed the material through the said opening.

30 2. An article of manufacture comprising a 40 rotor for breaking down materials, comprising a disc having pulverizing lugs extending from one side thereof parallel to the axis of the disc, the said lugs being outwardly tapering and of substantially elliptical cross section, the major axis of each lug being disposed substantially along the 45 arc of a circle circumscribed by the center point thereof during rotation, the said disc being provided with an opening therethrough, webs of propeller blade shape extending across the opening for feeding pulverized material through the 50 said opening and away from said lugs, a rim around the opening extending from the surface of the disc opposite to the surface from which the 55 said lugs project, the rim being bevelled at an angle preventing collection of pulverized material around the periphery of the opening.

3. An article of manufacture, a rotor for 60 breaking down materials, comprising a disc having pulverizing lugs extending from one face thereof, the rotor body being provided with an opening therethrough, through which opening pulverized material is adapted to feed, a rim extending around the opening and extending from the opposite face of the rotor body, the 65 said rim being bevelled at an angle preventing collection of pulverized material around the periphery of the opening, and reinforcing webs for the rim, the said webs extending across the opening and being provided with surfaces of propeller blade shape to pull pulverized material through the 70 said opening and away from said lugs.

ERNST W. SECKENDORFF.
